Primary Examiner—Lisa Lichtenstein

CLAIM

The ornamental design for an plug-in aerosol dispenser, as shown and described.

DESCRIPTION

FIG. 1 is a perspective view taken from in front of and above an plug-in aerosol dispenser incorporating the new design; FIG. 2 is a front elevational view of the plug-in aerosol dispenser of FIG. 1;

FIG. 3 is a first side elevational view of the plug-in aerosol dispenser of FIG. 1;

FIG. 4 is a rear elevational view of the plug-in aerosol dispenser of FIG. 1;

FIG. 5 is a second side elevational view of the plug-in aerosol dispenser of FIG. 1;

FIG. 6 is a top view of the plug-in aerosol dispenser of FIG. 1; and,

FIG. 7 is a bottom view of the plug-in aerosol dispenser of FIG. 1.
